MECHANICAL BRICK PRESS

Filed Jan. 25, 1928

Inventor:
Gaston Rigaux
Attorney:
John L. Smith

UNITED STATES PATENT OFFICE

GASTON RIGAUX, OF JUMET, BELGIUM

MECHANICAL BRICK PRESS

Application filed January 25, 1928, Serial No. 249,437, and in Belgium February 5, 1927.

My present invention relates to improvements in the well known mechanically operated brick and like presses, in which the clay to be pressed is introduced into feed-hoppers, whence the same is automatically brought 5 into moulds and finally automatically discharged from the latter as finished products.

More particularly my invention relates to an improved clay excavating mechanism of the type in which a series of cutters are mounted on a movable frame, provided with means for advancing as the cutters scrape clay from the front of a ditch formed by the machine, said clay excavating mechanism being combined with mechanical brick- 10 presses or the like for automatically treating the clay immediately after it being cut down.

The object of my invention is to provide an improved control mechanism for the cutters, said cutters being submitted to two distinct and independent motions; according to 15 my invention the cutters are mounted so as to move laterally towards the clay wall and then downwardly in a vertical direction, inversely laterally away from the wall and then upwardly in a vertical direction. Also the control mechanism is so arranged that the 20 displacement of the cutters in the vertical direction may be of great amplitude comparatively to the lateral displacement of the same.

Another object of my invention is to provide means whereby all the clay scraped down from the wall of clay is automatically conveyed to the feed hoppers of the brick-press or presses of the machine.

Therefore my invention consists in combining the well known mechanically operated brick presses with an improved device for breaking down clay, which will be directly brought into the feed hoppers of the press 40 by means of an automatic clay feeding device.

The improved clay cutting and conveying devices operated by the drive-shaft of the engine is illustrated by way of example in 45 the accompanying drawings as applied to a well known mechanical double brick-press; in these drawings:

Fig. 1 is the front elevation of the automatic clay cutting and conveying devices on 50 the motor chassis-frame of such a brick-

press, of which for sake of clearness the feed-hoppers only have been illustrated.

Fig. 2 shows the cutter-frame applied to the front of the press for breaking down clay.

A press of the kind set forth has two hoppers 2 and 3 suitably supported on a frame 8 and automatically supplying the moulds or the weighing devices connected thereto respectively with clay. As hereinafter described, the plastic clay or earth will be brought into the buckets 4 of an elevator 5, the endless bands or chains of which pass around two sprocket wheels 6 and 7 arranged on the frame 8 of the machine. The lower sprocket wheel 7 is loose, whilst the upper sprocket wheel 6 is driven by drive-shaft 1. A cable or chain 9 is wound around a sprocket rigidly connected with the sprocket wheel 6 as well as around a second sprocket 10 rigidly connected with the drive-shaft 1. Arranged above the hopper 3 is the end of a chute or gutter 11, the other end of which is located adjacent the sprocket wheel 6 in order to receive the clay discharged from the upsetting buckets of the elevator. Ending above the hopper 2 is a further chute or gutter 12 adapted to be rotated about a stationary axle 13.

Said axle 13 may be the suspension axle of 80 the hopper 2.

Intermediate the ends thereof the gutter 12 is supported on the crank arm 14 of a crank 15 attached to a sprocket 16, the latter being driven by the drive shaft through 85 the agency of a chain 17. Upon each revolution of the drive shaft or the sprocket 16 respectively the gutter 12 will thus be moved from the full line position into the dotted line position and vice-versa; in the full line position said gutter 12 will cover the stationary gutter 11 and therefore receive the entire mass of clay dropping from the buckets; upon the rotation of the gutter 12 the same will uncover the gutter 11 (which now 90 supplies the hopper 3), at the same time bringing the received mass of clay into the hopper 2. Therefore the clay supplying operation will be effected automatically by means of a single elevator for both hoppers 2 and 3. 100

The clay cutting or winning device proper comprises a vertical rigid frame 18, arranged at the front of the brick-press at right angles to the plane of Fig. 1. The frame 18 has a number of transverse cutters 20 which are removably arranged on holders 19 under a certain cutting angle.

The frame 18 is suspended in the slot 21 formed in a lever 22 adapted to swing about the pivot 23 on the frame 8, said lever having a second slot 24, engaged by the pin of a crank 25 arranged on the axle 26 of the sprocket 6.

On the other hand the frame 18 carries on either side two (or more) rods 27 adapted to rotate at 35 and loosely arranged on the axles of the rollers 28, said axles being connected together by means of longitudinal bars 29 to form a rigid frame, which is vertically slideable in guides 30 provided in the frame of the machine.

The rods 27 are rigidly connected to arms 31, each of which has an arcuate slot 32, the centre of which is located on the respective pivot pin 35 and which is engaged by a pin 33 on the frame 18. The frame formed by the longitudinal bars 29 extends with friction through a stationary block 34 which (by means of springs or the like) constitutes an adjustable brake for the vertical movements of the frame 29.

If in the upper position according to Fig. 1 of the cutter frame 18 it is supposed that the machine has just been moved forwardly as hereinafter described, the cutters 20 will be substantially in contact with the vertical wall 46 of the mass of clay. Now if the lever 22 is swung into the direction of the arrow, the entire device formed by the frame 18—29 will have tendency to move downwardly in a vertical direction; however such downward movement would be useless, since the cutters 20 would merely slide along the wall of clay. Owing to the calculated resistance of the brake 34 the frame 29 will be moved more slowly than the frame 18 and the levers 27, 31 rotatably arranged on the axles of the rollers 28, upon their downward movement, will cause the progressive substantially horizontal movement of the frame 18 towards the wall of clay, into which the cutters 20 will be inserted obliquely and moved at the same time downwardly, in order to cut down a layer of clay of a certain thickness. Upon the opposite movement of the swinging lever, the frame 18 will first be moved to the left hand side, whereupon the entire device 18—29 will be moved upwardly in a vertical direction, whereby the cutters 20 will be brought back into the position shown in Fig. 1, in order to permit the feeding movement of the machine and the movement of the cutters towards the new wall of clay.

The clay cut by the upper cutters will be received upon a chute 36, extending to the

cups of the elevator in order to fill the same; the clay cut by the lower cutters or dropping from the chute or slide 36 respectively will drop upon the ground in front of the machine, whence it will be brought to the cups of the elevator by means of a metal plate 37 which is longitudinally movable in the frame and actuated by means of a rod 38, pivotally connected at one end to the plate 37, and at the opposite end to a crank-arm 39 arranged on the axle of the lower sprocket wheel 7. Upon the sliding movement of the plate 37 on the ground in the direction of the arrow, the end 37' of said plate will slide under the clay cut by the lower cutters and bring the same below the casing 40 around the elevator.

The forward movement of the entire machine will be effected by means of an endless chain, said forward movement being determined by the drive-shaft in such a way that the same will take place during the upward movement of the cutter frame 18.

Preferably the machine is provided at the front with two metal plates 45 engaging the frame 18 and preventing clay from being sprayed laterally outside the frame 18 or the plates 36 and 37 respectively.

The chutes 11 and 12 for supplying the hoppers 2 and 3 with clay may be replaced by well known endless bands, with distributing shovels.

Preferably the chutes 11 and 12 as well as the elevator are housed within a casing in order to cover all the movable parts of the machine and avoid accidents.

It will be seen that the clay is cut down in the form of chips, whereby the regular weighing thereof for filling the moulds of the press, as well as the regular pressing thereof will be permitted. Owing to the cutting down in the form of thin chips, the superimposed layers of clay will be thoroughly mixed together and the products obtained will be of a uniform composition.

Having now fully described my said invention, what I claim and desire to secure by Letters Patent, is:

1. A device for cutting or breaking down clay for use in brick presses, comprising a drive shaft, feed hoppers for receiving the clay, a rigid frame carrying transverse cutters arranged one above the other, means actuated by said drive-shaft for moving said frame laterally, toward the clay wall and then downwardly in a vertical direction, and means for conveying the clay into the feed hoppers.

2. A device for cutting or breaking down clay for use in brick presses, comprising a drive shaft, feed hoppers for receiving the clay, a rigid frame carrying transverse cutters arranged one above the other, means actuated by said drive-shaft for moving said frame laterally toward the clay wall and then downwardly in a vertical direction, an

elevator for receiving the clay, and means for directing the clay from the elevator into the feed hoppers.

3. The combination of feed hoppers and a shaft, of a device for cutting or breaking down clay comprising a rigid frame carrying transverse cutters arranged above each other, a beam adapted to swing about a fixed axle and having a suitable slot wherein said cutter-frame is suspended, a crank mounted on 10 the shaft and cooperating with said beam to swing the same, a second rigid frame and means for guiding same in a vertical direction, said cutter-frame and second rigid frame being connected together by means of pivotally attached rods, arms rigidly connected to said pivotal rods, arcuate slots in said arms, pins on the cutter frame engaging said arcuate slots, and an automatically operating device for conveying the clay into one of the 20 feed-hoppers.

4. The combination with feed hoppers and a drive-shaft, of a device for cutting or breaking down clay comprising a rigid frame carrying transverse cutters arranged above each other, and means for moving said frame first towards the wall of clay and next downwardly in a vertical direction, a stationary inclined metal plate adapted to receive the 25 clay cut down by the upper cutters on said frame, and an elevator having a series of buckets receiving the clay from said metal plate, a horizontal metal plate arranged below said elevator and adapted to receive the clay cut down by the lower cutters, and means for reciprocating said horizontal plate along the ground, and an automatically operating device for conveying the clay into one of the feed-hoppers, and means for operating said 30 device from the drive-shaft.

40 In testimony whereof I have hereunto set my hand.

GASTON RIGAUX.
